CLAIM

The ornamental design for an outsole element of a shoe, as shown and described.

DESCRIPTION

FIG. 1 is a perspective view of the outsole element of a shoe showing my new design;

FIG. 2 is a plan view of the outsole element of a shoe shown in FIG. 1; and,

FIG. 3 is a front elevational view of the outsole element of a shoe shown in FIG. 1.

The phantom lines representing a shoe upper, portion of a shoe outsole and midsole shown in FIGS. 1-3 are for illustrative purposes only and form no part of the claimed design.
